Primary Examiner — Richard E Chilcot(74) *Attorney, Agent, or Firm* — Moss & Barnett;
Michael A. Bondi(57) **CLAIM**

The ornamental design for soap, as shown and described.

DESCRIPTION

1. Soap

Fig. 1.1 is a perspective view of the soap.

Fig. 1.2 is a top view of the soap.

Fig. 1.3 is a bottom view of the soap.

Fig. 1.4 is a first side view of the soap.

Fig. 1.5 is a second side view of the soap.

Fig. 1.6 is a first end view of the soap.

Fig. 1.7 is a second end view of the soap.
